UNITED STATES PATENT OFFICE.

FRANK B. CURRIER, OF ELIZABETH, NEW JERSEY.

MEADOW-TRENCHING MACHINE.

1,194,963.

Specification of Letters Patent. Patented Aug. 15, 1916.

Application filed March 5, 1915. Serial No. 12,252.

To all whom it may concern:

Be it known that I, FRANK B. CURRIER, a citizen of the United States, and a resident of Elizabeth, in the county of Union and State of New Jersey, have invented a new and Improved Meadow-Trenching Machine, of which the following is a full, clear, and exact description.

This invention relates to machines for digging drainage trenches in meadows, and has to deal more particularly with the bucket construction for digging and conveying away turf.

The invention has for its general object to provide a combined digging and conveying bucket of novel, simple and durable construction, and especially designed with the aim of causing the buckets to quickly and effectively discharge their contents, which is especially desirable in trenching machines, for the reason that the earth is heavy and soggy and is dumped with difficulty because of the vacuum or suction produced as the material attempts to drop out of the bucket when inverted, when the bucket is of that type having only one open face, and completely closed at all other points.

More specifically, the invention has for its object to provide a conveyer in which the back of the bucket is made up of slats separated one from another so as to provide spaces, the slats serving to retain material that is cut or dug by the bucket as the bucket moves upwardly out of the trench and to a considerable height where the point of discharge is located, and when the bucket is inverted to discharge its contents, the latter freely drops out, because there is an avoidance of all tendency to a suction or vacuum, because of the openings between the slats that form the wall of the bucket opposite from the open side, and by reason of this construction the buckets can operate at a maximum speed without the necessity of stopping the conveyer to clean out clogged buckets, which is an objection commonly encountered with buckets closed at all points except at the open side where the material enters.

With such objects in view, and others which will appear as the description proceeds, the invention comprises various novel features of construction and arrangement of parts, which will be set forth with particularity in the following description and claims appended hereto.

In the accompanying drawings, which illustrate one embodiment of the invention, and wherein similar characters of reference indicate corresponding parts in all the views, 60 Figure 1 is a plan view of a portion of a chain conveyer with the improved bucket construction; Fig. 2 is a side view of Fig. 1; Fig. 3 is a perspective view of the body of a bucket detached from the conveyer chain 65 or carrier; Fig. 4 is a sectional view showing the digging action of the buckets; Fig. 5 is a sectional view showing the dumping action of the buckets; Fig. 6 is a sectional view showing the range of movement of a 70 bucket during its dumping action; and Fig. 7 is a perspective view of one of the pairs of slats forming the back or bottom of the bucket.

Referring to the drawing A designates the 75 buckets and B the endless carrier or chain structure to which the buckets are attached, such endless carrier being designed for use in connection with any kind of trenching or other machine. The means for supporting 80 and driving the endless carrier B have not been shown, as the same form no part of the present invention.

As shown in Fig. 3, each bucket comprises 85 end walls 1 which are united by a connecting wall 2 that forms a cutter, scoop or shovel element whereby the turf or earth is dug in the manner shown in Fig. 4. In other words, the bucket is a U-shaped structure open at all points between the end walls 90 1, except the side where the cutter element 2 is located. The material is held in the bucket, however, by making use of the carrier B as a back or bottom for the bucket. This carrier B is made up of slats 3 arranged 95 side by side, but having their edges 4 spaced apart, and the leading portions of the buckets are pivotally connected with the endless carrier so that the body of the buckets can swing clear of the carrier at the point of discharge of the material, as shown in Figs. 5 and 6. Each slat 3, as shown in Fig. 7, has at its ends oppositely projecting apertured lugs 5, and the lugs of adjacent slats overlap, as shown in Fig. 1, and are connected by pins or rivets 6 which pass through the lugs. Associated with the ends of the slats are links 7 which are fastened to the slats by the pins or rivets 6, and interposed between the links 7 and ends of the slats and surrounding the rivets or pins 6 are spacing sleeves 8.

It will thus be seen that the endless carrier is made up of two parallel chains and intermediate connecting slats 3 and the pins 6 form abutments with which teeth on drive 5 sprockets or idlers engage to support and drive the endless carrier. The buckets are wider than the carrier, and the end walls 1 of the buckets lie outside the edges of the carrier. The leading portions of the end 10 walls 1 of the bucket body are provided with apertures 9, as shown in Fig. 3, and through these apertures extend the rivets 6, so that the bucket will have a swinging movement on an axis passing through the 15 leading portion thereof. In the present instance the carrier is shown with two slats to a bucket, but the number may be changed if desired. It is necessary to limit the clearing or swinging movement of the buckets 20 at the point of discharge, and for this purpose the end walls are provided with stops 10 which are adapted to engage with the carrier at a point ahead of the axis on which the bucket swings, as clearly shown in 25 Figs. 5 and 6. During the movement of a bucket from a point where material is received to a point where it is discharged, the trailing end of the bucket will bear against the carrier by the edge 11 of the cutting wall 30 2 bearing against the slats and links, as clearly shown in Fig. 4. Thus the carrier forms a backing which takes the thrust of the buckets during the cutting action, and the slats of the carrier serve to support the 35 turf or earth in the buckets, as the latter move to the point of discharge. When the point of discharge is reached, each bucket will swing on its pivot through an angle of about ninety degrees, and in swinging the 40 bucket moves away from the carrier so that the material can readily drop out without suction or vacuum interfering, as would be the case if the bucket was closed at all points except that side that receives the material. 45 As the end carrier makes a comparatively sharp turn at the point of discharge the slats associated with each bucket will move into the latter to a considerable extent and thereby assist in ejecting the material 50 and insure the self-dumping of the buckets.

From the foregoing description taken in connection with the accompanying drawing, the advantages of the construction and method of operation will be readily understood by those skilled in the art to which the invention appertains, and while I have described the principle of operation, together with the apparatus which I now consider to be the best embodiment thereof, I 55 desire to have it understood that the apparatus shown is merely illustrative and that

such changes may be made when desired as are within the scope of the appended claims.

Having thus described my invention, I claim as new and desire to secure by Letters 65 Patent:

1. In a machine of the class described, the combination of an endless conveyer including a series of transverse slats hingedly connected together, a series of buckets hingedly connected at their forward edges to the conveyer and each bucket being associated with a plurality of slats, whereby the latter form a bottom for holding material as the conveyer moves upwardly, and means on each bucket whereby the latter swings forwardly and downwardly at the point where the lower flight of the conveyer begins, whereby the bucket frees itself from the material. 70

2. An endless conveyer composed of 80 hingedly connected slats extending transversely to the length of the conveyer, buckets opened at the front and top and bottom and having only their front portions hingedly connected with the conveyer, whereby the 85 slats form the bottoms of the buckets to support the weight of the material on the upper flight of the conveyer, and stop means for the buckets arranged to permit the latter to swing forwardly and downwardly and 90 engage the conveyer to support the buckets in outstanding position with respect to the downward flight of the conveyer. 95

3. An endless conveyer composed of hingedly connected slats extending transversely to the length of the conveyer, buckets opened at the front and top and bottom and having only their front portions hingedly connected with the conveyer, whereby the slats form the bottom of the 100 buckets to support the weight of the material on the upper flight of the conveyer, and stop means for the buckets arranged to permit the latter to swing forwardly and downwardly and 105 engage the conveyer to support the buckets in outstanding position with respect to the downward flight of the conveyer, each bucket being of such size as to embrace a plurality of slats of the conveyer, whereby the slats arch upwardly into 110 the buckets where the upper flight merges into the lower flight, to thereby loosen the material in the bucket preparatory to the outward and downward swing of the buckets. 115

In testimony whereof I have signed my name to this specification in the presence of two subscribing witnesses.

FRANK B. CURRIER.
